US0D1043673S

(12) **United States Design Patent** (10) **Patent No.:** **US D1,043,673 S**
(45) **Date of Patent:** **** Sep. 24, 2024**

(54) **DISPLAY DEVICE**

(71) Applicant: **DCSTAR INC**

(72) Inventor: **Ligui He**, New York, NY (US)

(73) Assignee: **DCSTAR INC**, New York, NY (US)

(**) Term: **15 Years**

(21) Appl. No.: **29/861,440**

(22) Filed: **Nov. 30, 2022**

(30) **Foreign Application Priority Data**

May 30, 2022 (CN) 202230323763.5

(51) **LOC (14) Cl.** **14-02**

(52) **U.S. Cl.**

USPC **D14/371**; D14/159; D14/126

(58) **Field of Classification Search**

USPC D14/126, 131, 133-137, 305, 307,

D14/335-337, 340, 371-382, 448-451;

D21/324, 329; D10/1-5, 15, 21-23;

D6/304-310

CPC H04M 2201/50; H04M 2201/38; H04N

1/00302; H04N 2007/145; H04N 7/142;

G06F 1/1601

(57) **CLAIM**

The ornamental design for a display device, as shown and described.

DESCRIPTION

FIG. 1 is a front view of a display device showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a rear perspective view thereof.

The broken lines depict portions of the display device that form no part of the claimed design.

1 Claim, 8 Drawing Sheets
